SHEET DISPENSING DEVICE

Glenn A. Shaffer, Green Bay, Wis., assignor to
 Fort Howard Paper Company, Green Bay, Wis.,
 a corporation of Wisconsin

Application October 17, 1930, Serial No. 489,427

6 Claims. (Cl. 312—61)

The invention relates to dispensers and has as an object the provision of a floor type of dispenser adapted for dispensing folded sheets as paper napkins or the like.

5 It is an object of the invention to provide a dispenser which will contain a large number of folded sheets and automatically feed the same toward the dispensing openings.

10 It is a further object of the invention to provide a dispenser which is simple to manufacture and unlikely to get out of order.

It is a further object of the invention to improve generally upon details of devices of this character.

15 Further objects of the invention will appear from the following description when taken in connection with the accompanying drawings showing illustrative embodiments of the invention and wherein:

20 Fig. 1 is a plan view;

Fig. 2 is a transverse section on line 2—2 of Fig. 3;

Figs. 3 and 4 are vertical sections on lines 3—3 and 4—4 respectively of Fig. 2;

25 Fig. 5 is a vertical section of a modified form taken on line 5—5 of Fig. 6; and

Fig. 6 is a vertical section taken on line 6—6 of Fig. 5.

As shown in Figs. 1 to 4 inclusive the device 30 comprises a casing 10 adapted to seat upon the floor and desirably being of such a height as to bring the top within ready reach of users of the sheets, as folded napkins to be dispensed thereby.

The device is shown as embodying two dispensing elements whereby a double column of sheets may be provided for, although it is evident that a single column might be enclosed in a casing embodying the principles and structure shown in one-half of the illustration of both forms of the 40 device.

As shown the casing comprises a bottom 11 and end walls 12, 13, the latter extending substantially the full height of the device. The remaining sides of the casing are closed at the bottom by stationary panels 14, 15 and at the upper portion of the casing by movable panels 16, 17 seating between panels 12, 13 which may be made movable in any manner as for instance by hinges, 45 not shown, or readily removable completely from the casing.

The casing is shown as closed at the top by means of a cap 18 having a depending peripheral flange 19 standing in juxtaposition to the upper 50 ends of the side walls of the casing. To support

the cover 18 upon the casing, the cover is shown as formed with depending lugs 20 indicated as four in number extending inside the side walls 12, 13 and attached thereto as by screws 21.

The cover 18 is shown as formed with dispensing openings 22, 23, through which access may be had to sheets dispensed by the device, said sheets desirably being folded with a central tab which may be grasped by the user for removal of the sheet from the casing, as indicated for 65 instance in dotted lines in Fig. 1.

To support a column of folded sheets and elevate the same toward the openings 22, 23, there are shown movable platforms 24 in the form of plates having downturned edges 25 and central 70 angle members 26, the ends thereof projecting as at 27, 28 for attachment to the lifting sprocket chains 29, 30. Said chains 29, 30 are shown as passing about sheaves 31, 32 at the top of the casing and about sprocket wheels 33, 34, which 75 sprocket wheels are rigidly secured upon shafts 35 mounted in bearings 36, 37 mounted in plates 38, 39 in the bottom of the casing.

The chains are shown as endless but provided at portions which are not in the operation of the 80 device passed about the sprocket wheels or the sheaves with tension springs 40, 41 to take up wear and hold the chains tight.

To guide the sheets in their movement upon the platforms 24, there are shown plates 42, 43, 85 44, 45 mounted in the casing with their central edges spaced apart to provide slots or guideways for the projections 27, 28 of the angle 26.

The plates 42, 43 are shown as secured in the 90 casing by means of screws 46 engaging spacers 47 secured to the sides 12, 13 of the casing and the plates 45 may be screwed to the central partition 48. Openings 49 are shown in the plates 42, 43, for access to the screws 21 in the assembly 95 or disassembly of the device. To disassemble, the panels 16, 17 may be opened or removed, the screws 21 taken out, and the cover 18 removed, whereupon the plates 42—45 inclusive may be removed and the remaining parts are readily accessible for removal or adjustment.

To cause elevation of the platforms 24, there are shown coil springs 50 each secured at one end to a bracket 51 and at its remaining end to the sprocket 34 as at 52, sleeve 53, shown as formed 100 of wood, being loosely placed upon the shaft 35 for support of the convolutions of the spring.

It will be seen that when the device is assembled with the chains 29, 30 about the sprockets and the platforms 24 at the top of the device, 110

depression of the plates will tension the springs 50 and that the platforms will be elevated upon removal of the depressing power, after the manner of the Hartshorn shade roller.

6 To control the uncoiling of the spring 50, there is shown an escapement 55 in the form of a double pawl and a ratchet 56 secured upon the shaft 35, the action of escapement being under the control of pendulums 57 coacting with toothed discs 58 also carried by the shaft 35.

10 To stop the upward movement of the tables when the sheets to be dispensed are presented to or adjacent the openings 22, there are shown bars 59 pivoted upon a rod 60 at one end, said rod 15 passing longitudinally of the openings 22, 23 and out of the paths of movement of the sheets. Underlying the bar 59 at one end of the openings 22, 23 is a portion of a yoke 61 connected to a rod 62 passing downwardly outside the plates 42 20 and connected to an arm 63 pivoted as at 64 and provided with a notch 65 adapted to engage a lug 66 carried by the pendulum 57.

25 The rods 62 will fall by gravity when not supported by the sheets, thus allowing the pendulums 57 to swing freely and the spring 50 to unwind to elevate the platforms 24. When the top of the column of sheets reaches the openings 22, 28, or adjacent thereto, the rod 62 will be lifted so that notch 65 will engage the lug 66 and stop 30 movement of the pendulum thereby stopping feed of the sheets until the supply has been somewhat depleted.

35 The plates 38, 39 are desirably supported vertically as by means of a brace member or brace members 68.

40 To hold the platforms 24 at the bottom of their travel while sheets are being supplied thereon, there are shown sliding catches 69 having cam portions 70 adapted to enter openings 71 in the bars 26, the catches shown as being urged to engaging position by means of springs 72.

45 The catches are further shown as provided with extremities 73 to be engaged by the panels 16, 17. When the panels are removed the springs 72 will throw the catches outwardly to bring the cam portions into the path of the bar 26. If the platforms 24 are then depressed, the catches will engage the openings 71 and hold the platforms against tension of the springs 50. The supply 50 of sheets may then be replenished and when the panels 16, 17 are replaced pressure will be exerted upon the extremities 73 to overcome the springs 72 and release the catches allowing the elevation 55 of the sheets to take place automatically as described.

In the modification of Figures 5 and 6, a constantly running electric motor is utilized for elevation of the sheets and means are provided to cause the action of the motor to be operable or 60 non-operable upon the elevating platforms as required.

65 In this form of the device the platforms 75 provided with the central bars 76 have the ends 77, 78 projecting through slots 79 between the guide plates 80, 81 and attached to the sprocket chains 82, 83, all in a manner as already described in connection with Figures 1 to 4 inclusive. In this form of the device also the sprocket chains pass over sheaves 84, 85 and about sprockets 86, 70 87 and have tension springs 88 included for tightening the chains.

75 The sprockets 87 are shown as rigidly mounted upon drive shafts 89 driven by ratchet wheels 90 through the medium of pawls 91 mounted eccentrically upon an eccentric pin 92 driven by

a motor 93 through the medium of the reducing gear 94. The reversal of movement of the sprockets 86 by the pulls of the pawls 91 which would be caused by the weight of the sheets upon the platform 75 is prevented by pawls 95 pivoted at one end upon springs 96.

80 To control the elevation of the sheets by table 75, the pawls 95 are arranged to be lifted by means of rods 97 engaging the pawls at their lower ends and at their upper ends engaging bars 98 extending in the path of the ends of the folded sheets as elevated toward the dispensing openings 99, 100, said bars 98 being pivoted upon bars 101.

85 When the column of sheets upon the tables 90 engage the bars 98, the pawls 95 will be lifted and actuation of the pawls 91 by continuous action of the motor 93 will not result in advancement of the ratchets 90 tooth by tooth since the ratchet wheels are reversed each time the pressure of the pawls 91 is released under action of the eccentric pin 92. When the supply of sheets has been lowered, the rods 97 will allow the pawls 95 to fall into contact with the ratchet wheels 90 and the movement of the pawls 91 100 will become operative to feed the sheets upwardly.

90 In this form of the device it is to be understood that the side members 102, 103 are removable to give access to the interior of the device 105 for the purpose of replenishing the supply of the sheets. In such replenishment with the panels open, the pawls 95 may be lifted by pressure upon the projections 104 upon the pivot of the pawls thereby freeing the platform 75 which will drop 110 by gravity and the pawl may be held in lifted position while the supply of sheets is replenished.

95 To avoid excess of pressure of the sheets against the cover of the device, should the rods 97 fail to lift the pawls 95, the pawls are mounted as already described upon spring pivots 96. When undue pressure results, the reverse pressure upon the platform 75 will cause the ratchet wheels 90 to follow the strokes of the pawls 91 overcoming the resistance of the springs 98 so that the 120 ratchet wheels 90 instead of being driven will merely oscillate under action of the pawls 91.

115 Further minor changes may be made in the physical embodiment of the invention within the scope of the appended claims without departing 125 from the spirit thereof.

I claim:

1. A sheet dispensing device comprising, in combination, a casing, a vertical chute in said casing, an elevating platform movable in said chute, a spring motor, traction means driven by said motor, a flexible element secured to said platform and engaging said means, escapement mechanism governing the action of said motor, and means actuated by approach of the top of 130 a column of sheets on said platform to the top of said chute acting directly on said escapement mechanism to inhibit action of said escapement mechanism.

135 2. A sheet dispensing device comprising, in combination, a dispensing chute having a delivery opening, a follower movable in said chute to advance sheets to be dispensed toward said opening, a motor driven shaft having a traction element connected for moving said follower, a 140 motor comprising a source of constantly exerted energy to drive said shaft, a toothed wheel carried by said shaft, escapement mechanism acting on said toothed wheel to govern flow of said energy and means adjacent said opening to be 145 150

- contacted by advancing sheets operable to inhibit action of said escapement mechanism so as to hold said motor out of action while so contacted.
3. A sheet dispensing device comprising, in combination, a dispensing chute having a delivery opening, a follower movable in said chute to advance sheets toward said opening, a spring motor comprising a traction wheel constantly urged by a spring under tension, a flexible element engaging said wheel and connected to said follower, pendulum and escapement mechanism governing drive of said wheel by said spring, a detent to hold said pendulum, movable means adjacent said opening to be contacted by sheets approaching the opening and means connecting said movable means with said detent whereby presence of sheets adjacent said opening stops said motor.
4. A sheet dispensing device comprising, in combination: a casing having a dispensing opening; a follower for advancing sheets to said opening; a sprocket wheel and an idler, one adjacent each end of the range of movement of said follower; a sprocket chain passing about said idler and sprocket wheel and attached to said follower; a ratchet wheel for driving said sprocket wheel; a continuously acting motor; a pawl reciprocated by said motor and acting on said ratchet wheel; a holding pawl; and means to be pressed by sheets approaching said opening acting to lift said holding pawl to stop advancement of said follower by said motor.
5. A sheet dispensing device comprising, in combination: a casing, a pair of parallel chutes in said casing each having a sheet dispensing opening at an end thereof; a follower movable in each chute for advancing sheets to said openings; a continuously acting motor; pawl and ratchet mechanism for driving said followers; speed reducing gearing driven by said motor; a beam reciprocated through an eccentric driven by said gear, the pawls of said mechanism carried by the respective ends of said beam; a dog acting on each ratchet wheel; and means to be pressed by sheets approaching said openings to lift the respective dogs whereby to stop drive of the respective followers.
6. A sheet dispensing device comprising, in combination: a casing; a vertical chute in the upper part of said casing; an elevating platform movable in said chute; a horizontal shaft journaled in said casing below said chute; sprocket wheels mounted on the ends of said shaft; idler wheels adjacent the top of said chute; endless sprocket chains passing about said sprocket and idler wheels and secured to said platform; a motor for driving said shaft; a toothed wheel mounted on said shaft; a detent acting on said toothed wheel to govern drive of said shaft from said motor; liftable means adjacent the upper end of said chute in the path of movement of sheets upon said platform; and means to connect said liftable means with said detent whereby approach of sheets to the upper end of the chute will cause upward movement of the platform to stop.
